UNITED STATES PATENT OFFICE.

ISIDORE STERN, OF NEW ROCHELLE, NEW YORK.

DENTURE ATTACHMENT.

Application filed November 26, 1926. Serial No. 150,670.

This invention relates broadly to dentistry and more particularly to improvements in adjustable denture attachments for use in connection with removable bridge work.

5 The bridge work to which the invention relates involves primarily a removable bridge adapted to be disposed between two natural teeth, referred to as pier teeth in the dental art, and having a denture attachment at either end adapted to be removably secured within a socket or recess in a pier tooth. The denture attachment is secured within the socket by adjustable and/or resilient means, which takes up for wear occasioned by use 10 or service of the bridge and is capable of adjustment to compensate for such wear.

Each adjustable denture attachment preferably comprises generally two parts, to wit, a support which includes a shank formed on or secured to the bridge and a head unitary therewith upon which a resilient and/or adjustable means is carried for retention in the pier tooth socket.

The present invention seeks to provide 25 means to removably secure the support to the pier tooth with provision for adjustment in a simple manner, which means is not exposed when the bridge work is in position on the gums. To this end the said means 30 comprises a resilient element, such as a leaf spring, substantially the length of the head of the support which is permanently secured to the upper portion of the head as it is inserted in the socket and which is adapted to flex in the bottom of the socket to engage a wall thereof and retain the support therein.

The resilient element, or as it may be called, the adjustable or retaining element, 40 is secured to the head for approximately the upper half of its length, the lower portion being freely flexing, so that the dentist may cut away as much as is necessary of the support to cause it to conform to the occlusal surfaces of the teeth.

The invention also has for its object the provision of a simple and efficacious manner of securing the adjustable retaining member or spring to the support which will not be 45 affected by the removal of portions of the support and/or member in conforming it to the outlines of the teeth. Accordingly solder or other adhesive is availed of whereby every portion of the parts to be secured together are intimately joined. If desired

the head of the support may be provided with flanges along that portion with respect to which the spring flexes as guiding or positioning means therefor and the spring may be provided with flanges engaging the edges 60 of the head in continuation of the first named flanges to contribute to the positioning of the spring on the head and counteract torsional and shearing strains. If desired the flanges may be of curvilinear outline to facilitate insertion and removal in the socket.

Another object of the invention is the provision of a denture attachment which shall be practical from the standpoint of ease and simplicity of manufacture and facility in use.

The invention further seeks the provision of a denture attachment which is substantially reversible, that is, one which is effective whichever end of the shank is uppermost 75 when secured to the bridge work. To this end the resilient retaining element or adjustable leaf spring is secured to the head between its ends so that either end will function efficiently, that is flex to retain the support in the pier tooth socket although the uppermost end may be cut off and made to conform to the occlusal surfaces of the teeth. This construction is also advantageous due to the two springs involved as the retaining 85 pressure against the walls of the pier tooth socket is proportionately increased.

These and other objects of the invention and the means for their attainment will be more apparent from the following detailed 90 description, taken in connection with the accompanying drawings illustrating preferred embodiments of the invention, wherein Sheet 1 shows one form of the invention and Sheet 2 shows a modified form, in which:

Figure 1 is a view, in perspective showing bridge work mounted between spaced natural teeth by means of the adjustable denture attachment according to the present invention.

Figures 2, 3, and 4 are views showing the denture attachment with the resilient means removed, looking from above, from the rear and side elevation, respectively.

Figure 5 is a view, in perspective, showing 105 the resilient means for retaining the denture attachment in the pier tooth socket.

Figure 6 is a view of the denture attachment looking from above and showing the spring means and head in assembled relation.

Figure 7 is a view, in front elevation, of the denture attachment showing the adjustable spring in position.

Figure 8 is a longitudinal sectional view, 5 taken in the plane indicated by the line 8—8 in Figure 6, looking in the direction of the arrows, and showing the adjustment of the spring.

Figure 9 is a view of the denture attachment 10 in rear elevation.

Figure 10 is an exploded view in perspective, showing the denture attachment.

Figures 11, 12 and 13, are views similar 15 to Figures 2, 3 and 4 respectively, showing a modification of the denture attachment.

Figure 14 is a perspective view of a modified form of resilient adjustable securing means.

Figure 15 is a view of the modified denture 20 attachment looking from above and showing the adjustable means and head in assembled relation.

Figure 16 is a view, in front elevation, showing the modified denture attachment.

Figure 17 is a side view of the same showing 25 the adjustable resilient means in operative position.

Figure 18 is a view in rear elevation of the modified form of denture attachment.

Figure 19 is an exploded view, in perspective, showing the denture attachment in its 30 modified form.

Referring to Figure 1 for a general understanding of the invention, a dental bridge B, 35 representing, in this instance, one artificial tooth, is shown disposed between a pair of spaced natural teeth, P, P, growing in the gum G, designated, in the dental art, pier teeth. The bridge B, includes a saddle S, 40 say of gold or other suitable material, of any suitable form and serving as a permanent and rigid anchorage for the denture attachment forming the subject matter of the present invention.

The pier teeth P are provided with inlays L of gold or other suitable substance within 45 which are formed sockets or recesses 11 to receive the heads 12 integrally included with the shanks 13 of the respective denture attachments or supports D which thus have a T-shaped cross sectional area when considered in a normally horizontal plane. These inlays L with the recesses 11 formed therein 50 may be considered and referred to as socket receptacles, or separate socket receptacles 55 adapted to receive the T-shaped dentures or supports may be embedded in the inlays. The shanks 13 may be referred to as anchorage shanks and are embedded in or otherwise 60 suitably secured in rigid relation with the saddles S as shown.

The heads 12 are provided with adjustable securing means 16, preferably resilient, whereby when the denture attachments indicated as whole at D in Figure 1, are set into

the sockets 11, they will be retained therein and the bridge supported in desired relation to the natural teeth, as shown. The resilient means 16 preferably takes the form of a spring, say a leaf spring or a resilient plate, 70 which is adjustable to press against the walls of the recess 11 and retain the denture attachment D against accidental displacement.

In the illustrated embodiment the anchorage shank 13 is of rectangular form adapted 75 to be embedded in the saddle S and has integral therewith a head 12. On both edges of the head along the lowermost portion thereof, say the bottom half of the head the edges are formed with semi-cylindrical flanges 14 which form walls for that portion of the face 15 and define what may be termed 80 a groove. This groove may be considered as formed within a portion of the head of increased thickness, i. e. a thickness equivalent 85 to the thickness of the flanges, and the marginal surface of this portion of increased thickness is disposed in a plane parallel to the marginal surface of that portion of the head 12 which is without flanges. Between 90 these walls 14 is disposed a spring means of the present invention.

Cooperating with the head 12 is a resilient device or spring 16 preferably formed as a flat plate of substantially the size of the face 15 and having along its upper edges adjacent approximately the upper half thereof, semi-cylindrical beads or walls 17 corresponding to the flanges 14.

Upon assembly, the front face 18 of the 100 plate spring 16 is adapted to engage the face 15 of the head 12 with the flanges 17 engaging approximately the upper halves of the edges 19 of the head 12, while the lower portion 16^a of the spring lies between the 105 flanges 14 of the head.

The upper portions of the contacting faces 15 and 18, that is, those portions between the flanges 17 are caused to permanently adhere by a solder or other adhesive 110 20 (Figure 6) and as shown by stippling in Figure 10. Thus the upper portion of the spring 16 is caused to be rigidly and permanently secured to the head 12 and every portion of the contacting surfaces are secured together, the flanges 17 contributing to the 115 rigidity of the connection as will be apparent.

The lower portion 16^a of the spring 16 is free to flex in the channel formed by the 120 flanges 14 on the head 12. This portion 16^a forms the adjustable resilient securing means for the denture attachment D in the socket 11. By the insertion of a tool or other instrument between the freely flexing spring 125 end 16^a and the face 15 on the head 12 the spring end may be deflected outwardly or set as shown in dotted lines in Figure 8 so that upon insertion in the socket 11 the outwardly deflected spring end 16^a will engage 130

against a wall of the socket and frictionally retain the denture attachment, and hence the bridge, against displacement.

The rounded surfaces of the flanges 14 and 17 form a continuous curvilinear edge which facilitates the insertion of the denture attachment in the socket and simplifies the formation of the walls of the sockets since square corners and the necessary labor in truing the same are obviated. They also form a continuous surface along either edge of the deflected spring which is convenient in inserting the denture attachment in the pier tooth.

As viewed in Figure 7, the transverse dimension of the flexing spring leaf 16^a is slightly less than the transverse width of the face 15 between the flanges 14 to afford a clearance 21 at each side for freedom of movement of the spring.

According to the modification described the effective portion of the spring 16 is disposed at the lower portion of the denture attachment D and is thus in the bottom of the socket 11 when inserted in the pier tooth P. The upper half 16^b of the spring leaf is ineffective as a resilient device, being utilized, according to this modification, solely as an adhering or securing portion. Thus the dentist may freely cut away the upper portion of the denture attachment, including the top portion 16^b of the spring, to conform it to the occlusal surfaces of the teeth without affecting the operativeness of the spring as a resilient retaining device.

Figures 11 through 19 illustrate a modification of the denture support wherein the shank 13 for anchoring to the saddle S is similar to that already described.

According to this modification, the head 12 is provided with flanges 114, preferably outwardly semi-cylindrical, extending substantially the entire length of the vertical edges thereof as viewed in Figure 19, but interrupted by recesses or cut away portions 30 between the ends thereof. The recesses 30 extend substantially through the thickness of the flanges 114, and, in effect, divide the said flanges into two longitudinally spaced flanges 114^a and 114^b.

The modified adjustable means for securing the support D within a pier tooth socket comprises a rectangular resilient plate 116 adapted to lie within the walls or flanges 114 and contact with the surface 115 on the head. Both ends of the plate 116 are adapted to flex, in this modification, between the walls 114 and to this end a portion between the ends thereof is adhesive to a solder interposed between the portion 120 on face 115 and the corresponding portion on the plate 116. Thus a pair of resilient wings is formed which may be individually deflected outwardly so as to yieldingly engage the walls of the socket.

To further fasten the plate spring 116 against displacement and counteract shear the adjustable member 116 is provided with a pair of lugs 117, adjacent the portion adhesive to solder and adapted to enter the recesses 30 and be soldered therein if desired. These lugs are preferably of curvilinear outline to continue the outer marginal surfaces of the walls 114.

In the modified construction a tool may be inserted between the head and either or both wings 116^a, 116^b to deflect them outwardly away from the face 115 a distance sufficient to cause them to yieldingly bear against the walls of the pier tooth socket when inserted.

The modified structure as described is reversible, that is, either end may be uppermost when anchored on the bridge saddle and whichever end is uppermost may be whittled away by the dentist in conforming the support D to the occlusal surfaces of the teeth without affecting the adequacy of the fastening within the socket. The modification has an advantage in some situations since two resilient wings are provided which may bear with equal intensity or with proportional effect on the walls of the socket.

Various modifications may be made in the configuration and composition of the resilient retaining means associated with the denture attachment and in the cooperating flanges thereon as well as in the application of the denture attachment as a whole and no limitation is intended by the phraseology of the foregoing description or illustrations in the accompanying drawings except as set forth in the appended claims.

What I claim is:

1. In a denture attachment, a T-shaped support having a head, flanges carried with the head along opposite sides thereof, a leaf spring, flanges carried with the spring to overlie the sides of the head, and means to secure the leaf spring to the head to flex between the first named flanges.

2. In a denture attachment, a T-shaped support having a head, flanges carried with the head along opposite sides for approximately half the length thereof, a leaf spring, flanges carried with the spring to overlie the sides of the head for the remainder of its length and means to secure the spring to the head between the last named flanges.

3. In a denture attachment, a support having a head formed with a face comprising two portions having corresponding marginal surfaces lying in two parallel planes, one portion being formed with a groove having its bottom surface in the plane of the marginal surface of the other portion, adjustable means disposed in the groove and means to secure the adjustable means to the surface of the other portion.

4. In a denture attachment, a support

having a head formed with a face comprising two portions having corresponding marginal surfaces lying respectively in two parallel planes, one portion being formed with 5 a groove having its bottom surface in the plane of the marginal surface of the other portion, adjustable securing means formed with a face comprising two portions having 10 corresponding marginal surfaces lying respectively in two parallel planes, one portion being formed with a groove having its bottom substantially in the plane of the marginal surface of the other portion, the ungrooved face of the securing means lying 15 in the grooved face of the head and the un-

grooved face of the head lying in the grooved face of the securing means.

5. A denture attachment for removable bridge work comprising a T-shaped support having a shank to be secured to the 20 bridge and a head for insertion in the socket, flanges carried by the head along opposite sides for approximately half its length, a leaf spring, flanges carried with the leaf spring along opposite edges to overlie the 25 remainder of the sides of the head, and means to secure the spring to the head to flex between the flanges thereon.

In testimony whereof I affix my signature.
ISIDORE STERN.
